UNITED STATES PATENT OFFICE.

JOB M. S. FRUIT, OF GOTHAM, WISCONSIN.

DESIGN FOR A BASE OR BACK FOR CLOTHES-RACKS.

No. 37,741.

Specification for Design.

Patented Dec. 19, 1905.

Application filed August 24, 1905. Serial No. 275,676. Term of patent 7 years.

To all whom it may concern:

Be it known that I, JOB M. S. FRUIT, a citizen of the United States, residing at Gotham, in the county of Richland and State of Wisconsin, have invented a new, original, and ornamental Design for a Clothes-Rack Base or Back, of which the following is a specification, reference being had to the accompanying drawing, forming a part thereof.

The figure is a perspective view of a base or back for a clothes-rack, showing my new design.

I claim—

The ornamental design for a base or back for a clothes-rack, as shown.

JOB M. S. FRUIT.
